PRINTING PLATE

Thomas W. Gittus, Toledo, Ohio, assignor to Toledo Scale Corporation, Toledo, Ohio, a corporation of Ohio

Filed Mar. 13, 1959, Ser. No. 799,351

12 Claims. (Cl. 101—384)

This invention relates to printers for tickets, labels or the like, and more particularly to attachments for such printers for printing successive labels with different information.

The printing attachments are particularly useful in the printing apparatus which is shown and described in co-pending U.S. application Ser. No. 791,728 filed February 6, 1959 in the names of C. E. Adler and F. C. Carroll. Such printing apparatus is described, for the purpose of illustration, in connection with a weighing scale, the scale and the printing apparatus being constructed as a unit to weigh commodities and to issue a printed ticket bearing thereon the net weight, price per pound, and computed value of a weighed commodity together with such variable data as the date, store code, commodity name, and commodity grade.

Where successive labels must be provided with different information, e.g., in connection with labeling of packaged meats in food stores, the changing of the printing type in the printing apparatus constitutes an important element of time and cost. Several labels may bear information as to the cut, e.g., "Rib Roast" and the grade, e.g., "U.S. Choice" either one or both of which informations must be changed for printing the next group of labels. Furthermore, such information must be properly positioned so that no overlapping of the various printed matter occurs.

Heretofore, some printers for tickets, labels or the like had channeled drums holding lines of type. Such printers are not satisfactory for printing successive labels with different information, since much time is consumed in transferring and positioning the type. Other prior printers for tickets, labels or the like had printing plates, in lieu of channeled drums holding lines of type, which bore embossed printing indicia for printing both the commodity names and commodity grades. An example of such a printer is shown and described in U.S. Patent No. 2,839,995 issued June 24, 1958 in the names of R. O. Bradley and B. E. Robinson. Although generally satisfactory such printing plates are expensive because of the great number required for each printer, the great number being necessary because the plates were used to print both the commodity names and commodity grades. In order to print five labels with the five different U.S. grades of beef, even though each of the five labels was printed with the same commodity name such as "Rib Roast," five of the prior printing plates were required.

Furthermore, the channeled drums holding lines of type and the printing plates and their holders shown and described in the foregoing patent are useful only in conventional rotary printing machines whereas in the printing apparatus shown and described in the foregoing application, in which the printing attachments of the invention are particularly useful, the printing type are stationary and means, such as a roller printer, presses an element to be printed against such printing type.

It is, therefore, the principal object of this invention to provide improved means for removably fixing print-

2

ing indicia in proper position in a printer for tickets, labels or the like.

Another object of the invention is to provide a pair of cooperating printing plates which are readily detachable from each other, one of the plates printing information of a first kind and the other printing information of a second kind, whereby a relatively large number of combinations of said two kinds of information can be printed from a relatively small number of printing plates.

10 Another object of the invention is to provide a printing plate which functions additionally as a holder for a second printing plate, one of the plates printing a commodity name and the other printing a commodity grade, whereby the total number of plates needed in a set used in foodstore prepackaging is kept relatively small by using the same commodity grade plate with several of the commodity name plates.

15 A further object of the invention is to provide an improved printing plate for a printer for tickets, labels or the like.

20 Still another object of the invention is to provide an improved holder for such printing plate in which the plate is easily and accurately positioned and from which the plate is readily detachable.

25 Another object of the invention is to provide, in a printer for tickets, labels or the like, a printing plate holder which is easily and accurately located in proper position in the printer and which is readily detachable from the printer, the holder itself functioning additionally in certain instances as a printing plate, and a printing plate which is easily and accurately so located in proper position in the holder that any printing type on the holder and the printing type on the printing plate are juxtaposed and which is readily detachable from the holder.

30 These and other objects and advantages will be apparent from the following description of a preferred form of the invention.

According to the invention, a pair of cooperating printing plates is provided for a printer for printing tickets, labels or the like. One of the plates prints information which is different from that printed by the other. In instances where different labels are printed with some information which is common to all, it is possible to reduce 45 the overall number of the plates by using a common plate for the common information. For example, where successive labels are provided with different information in connection with the labeling of prepackaged beef in food stores, the common information is the grade 50 of the particular beef being packaged while the variable information is the name of the cut such as "Rib Roast," etc. Heretofore, the printing of "U.S. Choice Rib Roast" and "U.S. Prime Rib Roast" required two of the commodity plates which are shown and described in the foregoing U.S. Patent No. 2,839,995. In contrast, the same printing is performed by one of the commodity name plates (Rib Roast) of the invention by changing the commodity grade plates (U.S. Choice and U.S. Prime) of the invention which cooperate with such commodity name plate. Since there are only five U.S. grades of beef, only five of the commodity grade plates are needed for a complete set. These five plates reduce the overall number 55 of the plates in the set by many times five.

60 The commodity grade plate is in the form of a holder which is easily and accurately located in the printer. This holder may or may not bear printing indicia. For example, there are no grades of cheese, luncheon meat, etc., while beef is graded U.S. Prime, Choice, Good, Utility, or Commercial. The commodity name plate is easily and accurately located in the holder; it is readily removable either by removing the holder from the printer or by removing the name plate from the holder. When

in place in the holder, the printing type on the name plate are juxtaposed to any printing type on the holder. Both the commodity grade and commodity name plates are formed with easy to grasp handle means, formed to be located in the printer in one position only, and have identification indicia in view of the operator so that he can tell at a glance which plates are in the printer.

In processing a side of beef, the commodity grade plate is chosen which corresponds to the grade of the beef being processed. This plate is positioned in the printer and is not disturbed as long as that grade of beef is being processed. Commodity name plates are substituted one for the other as the various cuts from the side of beef are prepackaged. The printing, for example, of "U.S. Choice Rib Roast" and "U.S. Choice Sirloin Steak" requires one of the grade plates and two of the commodity plates.

A preferred embodiment of the invention is illustrated in the accompanying drawings.

In the drawings:

Fig. I is a plan view of the printing plates of the invention in their operative positions in a printer, the printer being shown only fragmentarily;

Fig. II is a front elevational view of the device shown in Fig. I;

Fig. III is a side elevational view of the device shown in Fig. I; and

Fig. IV is an exploded view in perspective of the printing plates shown in Figs. I-III.

These specific figures and the accompanying description are intended merely to illustrate the invention but not to impose limitations on the claims.

The printing plates 1 and 2 of the invention are shown at a printing station in Figs. I-III in operative positions in a frame 3 of a printer which for the purpose of illustration can be considered to be the printer for tickets, labels or the like which is shown and described in the foregoing application Ser. No. 791,728. Tickets or labels (not shown) are pressed against the printing plates after they are inked as described in the application by a platen roller 4 as also described in the application.

Printing plate 1 functions both as a printing means and as a holder for the other printing plate 2; it includes a flat printing plate supporting portion 5, a part or edge 6 of which is bent or turned up out of the plane of the supporting portion 5. The bent part 6 of the printing plate 1, which is the front portion of the plate, functions as a place to put identification indicia 7 which correspond to the printing type 8 carried by the supporting portion 5 of the printing plate. These type 8 can be made, for example, of rubber, metal, or plastic and can be formed integrally with the plate or made separately and attached by means of an adhesive and are used to print a first kind of information, for example, the grade of beef being prepackaged, such grades being U.S. Prime, Choice, Good, Utility and Commercial. For commodities, such as cheese or luncheon meat, which are not graded the area on the plate occupied by the type 8 is left blank. Hence, six of the printing plates 1 are needed for a complete set, five for the five grades of beef and one for the blank, and are termed "commodity grade printing plates." The commodity grade printing plate 1 also carries type 9 for printing a store code.

The bent part or front portion 6 of the printing plate 1 also functions as a support for a pair of locating and latch pins 10 each of which includes a pair of spaced shoulders 11 and a portion which extends through the front portion 6 of the printing plate 1 to receive a knob handle 12. The pins 10 are received in horizontal openings 13 in the frame 3 with the shoulders 11 that are remote from the handles 12 against abutment surfaces 14 of the frame to accurately locate the type 8 and 9 in the printer and with the upper surface of the type bearing portion 5 of the printing plate 1 against an abutment surface 15 of the frame 3 to impart stability to

the printing plate 1. It is vital that the printing type 8 and 9 be accurately located in the printer so that no overlapping of the various printed matter occurs, the printer printing and issuing a ticket or label bearing thereon the net weight, price per pound, and computed value of a weighed commodity together with such variable data as the date, store code, commodity name, and commodity grade, the store code, commodity name and grade being printed by the printing plates of the invention.

10 A slide keeper 16 supported on the shoulders of shoulder screws 17 carried by the frame 3 above the abutment surfaces 14 of the frame is selectively slidable between a locked and an unlocked position as determined by the length of slots 18 in the keeper that cooperate with the shoulder screws 17. In the locked position which is shown in Figs. I-III, tongues 19 on the slide keeper 16 are received in a tight fit between the spaced shoulders 11 on the pins 10 to hold the commodity grade printing plate 1 in place, the printing plate 1 being readily removable from the frame 3 of the printer by sliding the keeper 16 to its unlocked position and withdrawing the pins 10 from the openings 13 in the frame.

20 The commodity grade printing plate 1 which functions additionally as a holder for the other printing plate 2 is provided with a slot 20 which extends from the front portion 6 of the plate 1 toward the printing type 8 on the plate, the slot 20 being transverse to such type 8 and having an enlarged open end 21 at the front portion 6 and a closed end 22 remote from the front portion 6. A spring clip or keeper 23 is secured to the type bearing portion 5 of the plate 1 at the closed end of the slot with its open mouth facing the slot, the spring clip 23 being on the upper surface of the type bearing portion 5 and the type 8 being on the lower surface of the type bearing portion 5.

30 The printing plate 2 includes a flat portion 24 bearing type 25 for printing a second kind of information a minor part or front portion 26 of which type bearing portion is bent out of the plane of the type bearing portion and which is suitable for use as a handle and as a place to put identification indicia 27 corresponding to the type 25. Three shouldered guide and lock pins 28 are carried by the upper surface of the type bearing portion 24 of the printing plate, the lower surface of the type bearing portion 24 being the surface on which the type 25 are located, in a straight row which extends transverse to the front portion 26 of the plate and to the type 25 on the plate.

40 The printing plate 2 is inserted in the holder 1 by moving it in the direction indicated by the arrow in Fig. IV to insert the first one of the pins 28 in the enlarged open end 21 of the slot 20 and then the other two of the pins until such first pin contacts the closed end 22 of the slot. The edges of the printing plate 1 along the slot 20 fit snugly between the shoulders on the pins 28 and the upper surface of the type bearing portion 24 of the printing plate 2. A head 29 on such first one of the pins 28 expands the spring clip 23 as it approaches the closed end 22 of the slot 20, the clip resiliently returning to its original position to embrace the head 29 when the printing plate 2 is inserted fully in its holder 1 to retain the plate 2 in the holder in a readily removable condition. In the inserted position, the type 25 on the printing plate 2 are juxtaposed to the type 8 on the holder or commodity grade printing plate 1 in an accurately located position, the type 8 printing the grade of the beef being prepackaged and the type 25 printing the name of the cut of the beef being prepackaged. Hence, the printing plate 2 is termed 50 "commodity name printing plate." The commodity name printing plate 2 can be readily removed from the printer either by sliding it out of the slot 20 in the commodity grade printing plate or holder 1 or by removing the holder 1 from the frame 3 of the printer as hereinbefore described.

In operation, in processing a side of beef, a commodity grade printing plate or holder 1 is chosen which corresponds to the grade of the beef being processed. The identification indicia 7 aids in the selection. The printing plate or holder 1 is locked in the printer by means of the slide keeper 16, the shoulders 11 remote from the handles 12 on the pins 10 locating the holder accurately relative to the printing station in operative position and the slide keeper locking the holder in such position. The type 8 carried by the holder prints information of a first kind, i.e., the grade of the beef, and is left in the printer as long as the grade of the beef being prepackaged remains unchanged.

Commodity name printing plates 2 are substituted one for the other in the holder 1 in operative positions accurately located, by means including the closed end 22 of the slot 20 in the holder, relative to the printing station as the various cuts of beef are prepackaged. Type 25 carried by the printing plates 2 print information of a second kind, i.e., the names of the cuts of beef. Since the commodity name plates 2 are readily detachable from the holder 1, a relatively large number of combinations of said two kinds of information can be printed from a relatively small number of printing plates. Of course, the two kinds of information can be information other than commodity grades and names depending upon the particular use to which the printer is put.

In processing commodities which do not have grades, such as cheese and luncheon meat, a holder 1 is chosen which does not carry printing type, i.e., it is a blank. Commodity name printing plates 2 are substituted one for the other in the holder 1 as the various commodities are prepackaged.

Various modifications may be made in specific details of construction without departing from the spirit and scope of the invention.

Having described the invention, I claim:

1. In a printer for tickets, labels or the like, in combination, a frame, a pair of cooperating printing plates, a first one of the plates having a type bearing portion, a front portion out of the plane of the type bearing portion and latch means on the front portion, the second one of the plates also having a type bearing portion, there being a slot in one of the type bearing portions, means on the other one of the type bearing portions received in the slot to guide the second plate into a position wherein the type on the plates are juxtaposed, resilient means for retaining the plates in such position, and keeper means on the frame which cooperate selectively with the latch means on the first plate for holding the first plate in a stationary position on the frame, whereby the second plate can be readily removed from the printer either by removing it from the first plate or by removing the first plate from the printer.

2. In a printer for tickets, labels or the like, in combination, a frame, a pair of cooperating printing plates, a first one of the plates having a type bearing portion, a front portion out of the plane of the type bearing portion and latch means on the front portion, the second one of the plates also having a type bearing portion, there being a slot having a closed end in one of the type bearing portions, a keeper at the closed end of the slot and means on the other one of the type bearing portions received in the slot and retained by the keeper to hold the type on the plates juxtaposed, and keeper means on the frame which cooperate selectively with the latch means on the first plate for holding the first plate in a stationary position on the frame, whereby the second plate can be readily removed from the printer either by removing it from the first plate or by removing the first plate from the printer.

3. In a printer for tickets, labels or the like, in combination, a frame, a pair of cooperating printing plates, a first one of the printing plates having a type bearing portion and a front portion out of the plane of the type bearing portion and a

bearing portion, latch means on the front portion, a slot in the type bearing portion extending from the front portion, the end of the slot remote from the front portion being closed, and a spring keeper at the closed end 5 of the slot, the second one of the printing plates also having a type bearing portion and means received in the slot and retained by the spring keeper to hold the printing type on the plates juxtaposed, and keeper means on the frame which cooperates selectively with the latch means on the first plate for holding the first plate on the frame, whereby the second plate can be readily removed from the printer either by sliding it out of the slot in the first plate or by removing the first plate from the printer.

4. In a printer for tickets, labels or the like, in combination, a frame, a pair of cooperating printing plates, a first one of the printing plates having a type bearing portion, a front portion out of the plane of the type bearing portion and a handle on the front portion, the second one of the printing plates also having a type bearing portion and a front portion out of the plane of the type bearing portion, there being a slot in one of the type bearing portions extending transversely to the type thereon, the slot having an open end at the front portion of the printing plate and a closed end remote from the front portion, means on the other one of the type bearing portions received in the slot to guide the second plate into a position wherein the type on the plates are juxtaposed, resilient means for retaining the plates in such position, the 20 front portion of the second plate functioning both as a handle and as a place to put identification indicia corresponding to the type on the type bearing surface of the second plate, and keeper means on the frame which cooperates selectively with the latch means on the first plate for removably holding the first plate on the frame.

5. In a printer for tickets, labels or the like, in combination, a frame, a pair of cooperating printing plates, a first one of the printing plates having a type bearing portion, a front portion out of the plane of the type bearing portion and a handle on the front portion, a slot in the type bearing portion extending from the front portion transversely to the type thereon, the slot having an open end at the front portion and a closed end remote from the front portion, and a keeper at the closed end of the slot, the 40 second one of the printing plates having a type bearing portion, a front portion out of the plane of the type bearing portion and means received in the slot and retained by the keeper to hold the type on the printing plates juxtaposed, the front portion of the second plate functioning both as a handle and as a place to put indicia corresponding to the type on the type bearing surface of the second plate, and keeper means on the frame which cooperates selectively with the latch means on the first plate for removably holding the first plate on the frame.

6. The combination of a pair of printing plates for a printer for tickets, labels or the like comprising a first printing plate having a type bearing portion, a front portion out of the plane of the type bearing portion remote from the type on the type bearing portion, a slot in the type bearing portion extending from the front portion toward such type, the slot having an open end at the front portion and a closed end remote from the front portion, 60 and a spring clip at the closed end of the slot, and a second printing plate having a type bearing portion, a front portion out of the plane of the type bearing portion remote from the type on the type bearing portion and means slidable in the slot and received in the spring clip to hold the printing type on the plates juxtaposed.

7. The combination of a pair of printing plates for a printer for tickets, labels or the like comprising a first printing plate having a type bearing portion, a front portion out of the plane of the type bearing portion and a

handle on the front portion, such front portion being suitable for carrying identification indicia corresponding to the type on the first plate, and a second printing plate having a type bearing portion and a front portion out of the plane of the type bearing portion and remote from the type on the type bearing portion, the front portion functioning both as a handle and as a place to put identification indicia corresponding to the type on the second plate, one of the type bearing portions having a slot extending from the front portion toward the type on such type bearing portion, the slot having an enlarged open end at the front portion and a closed end remote from the front portion, the other one of the type bearing portions having means insertable in the enlarged open end of the slot and slidable in the slot, and a spring clip on one of the plates which cooperates with the other one of the plates to hold the printing type on the plates juxtaposed.

8. The combination of a pair of printing plates for a printer for tickets, labels or the like comprising a first printing plate having a type bearing portion, a front portion out of the plane of the type bearing portion remote from the type on the type bearing portion, a handle on the front portion, such front portion being suitable for carrying indicia corresponding to the type on the first plate, a slot in the type bearing portion extending from the front portion toward the type, the slot having an enlarged open end at the front portion and a closed end remote from the front portion and a spring clip at the closed end of the slot, and a second printing plate having a type bearing portion and a front portion out of the plane of the type bearing portion remote from the type on the type bearing portion, the front portion functioning both as a handle and as a place to put indicia corresponding to the type on the second plate, and means insertable in the enlarged open end of the slot, slidable in the slot and receivable in the spring clip to hold the printing type on the plate juxtaposed.

9. The combination of a printing plate and a holder therefor for a printer for tickets, labels or the like comprising a holder member having a printing plate supporting first portion with a second portion out of the plane of the supporting portion, and a printing plate member having a type bearing first portion and a second portion out of the plane of the type bearing portion remote from the type on the type bearing portion, the second portion of the plate functioning as a handle and as a place to put indicia corresponding to the type, one of the members having a slot in its first portion with an enlarged open end and a closed end, the other one of the members having means insertable in the enlarged open end of the slot and slidable in the slot to position the type on the plate remote from the second portion of the holder, and means on one of the first portions for retaining the plate in the holder in such position.

10. The combination of a printing plate and a holder therefor for a printer for tickets, labels or the like comprising a holder having a printing plate supporting first

portion with a second portion out of the plane of the first portion, a slot in the first portion having an enlarged open end at the second portion and a closed end remote from the second portion and a spring clip at the closed end of the slot, and a printing plate having a flat type bearing surface, an edge out of the plane of the type bearing surface remote from the type on the type bearing surface, the edge functioning both as a handle and as a place to put indicia corresponding to the type, and means insertable in the enlarged open end of the slot, slidable in the slot and receivable in the spring clip to retain the printing plate in the holder.

11. In a printer for tickets, labels or the like, in combination, a frame, a printing plate holder having a printing plate supporting portion and an up-turned front edge, latch means on the front edge, a slot in the supporting portion extending from the front edge, the end of the slot remote from the front edge being closed, and a spring keeper at the closed end of the slot, a printing plate having a type bearing surface and means received in the slot and retained by the spring keeper to retain the printing plate in the holder, and keeper means on the frame which cooperates selectively with the latch means on the holder for holding the holder on the frame, whereby the printing plate can be readily removed from the printer either by sliding it out of the slot in the holder or by removing the holder from the frame.

12. In a printer for tickets, labels or the like, in combination, a frame, a printing plate holder having a printing plate supporting portion with an up-turned front edge, latch means on the front edge, a slot in the supporting portion having an enlarged open end at the front edge and a closed end remote from the front edge and a spring clip at the closed end of the slot, the front edge functioning as a handle, a printing plate having a type bearing surface, a front edge out of the plane of the type bearing surface remote from the type on the type bearing surface, the front edge functioning both as a handle and as a place to put identification indicia corresponding to the type, and means insertable in the enlarged open end of the slot, slidable in the slot and receivable in the spring clip to retain the printing plate in the holder, and means on the frame which cooperates selectively with the latch means on the holder for holding the holder with its detachable printing plate on the frame.
